ATTORNEY.

UNITED STATES PATENT OFFICE

2,143,250

CONTAINER

Carl Arnold Ritter, Chicago, Ill.

Application October 22, 1937, Serial No. 170,368

5 Claims. (Cl. 221—15)

This invention relates to new and useful improvements in containers, and more particularly to an outlet for oil or gasoline containers and the like.

One of the objects of the invention is to provide an outlet for a container which is normally closed by a spring urged valve.

Another object of the invention is to provide a valve which when released opens communication between the container and an air chamber.

Another object is to provide an air inlet to the chamber.

Another object is to provide a container having a chamber provided with an air inlet adapted to allow free flow of a liquid from the container through the outlet of the chamber.

With these and other objects in view the invention will be better understood by reference to the accompanying drawing and specification wherein like numerals represent corresponding parts and wherein:

Fig. 1 is a cross sectional view of the device and

Fig. 2 is a top plan view.

Referring more particularly to the drawing 1 indicates a container having an opening 2 at the upper end thereof. Mounted at the inner face of the top wall 3 of the container 1 is a reinforcing washer 4. Mounted over the opening 2 is a dome 5 having a depending neck 6 adapted to be inserted through the opening 2 and peened as at 7 to the under face of the washer 4 whereby to lock the dome 5 to the container 1.

The upper end of the dome 5 is internally threaded as at 8 to receive a closure 9. Arranged in a recess 9a formed in the closure 9 is a gasket 9b adapted to seal the upper end of the dome 5. The closure 9 is provided with a center bearing 10 adapted to slidably receive a valve stem 11. A gasket 10b is arranged in a recess 10a formed in the lower end of the bearing 10. The valve stem 11 has a valve 12 attached at its lower end which is adapted to rest upon a valve seat 13 formed in the lower wall 14 of the dome 5. The dome 5 is provided with an outlet 15 at one side thereof to which a flexible spout or the like may be threaded if desired. An air inlet is provided at the other side of the dome as shown at 16. A compression spring 17 is mounted around the stem 11 with its upper end in abutment with the gasket 10b and its lower end against the upper face of the valve 12. The gasket 10b serves to prevent leakage of liquid through the bearing 10. A compression spring 18 is mounted between the closure 9 and the valve 12.

Pivotedly connected at one side of the dome 5 as shown at 19 is a lever 20. The lever 20 is connected as shown at 21 to any suitable toggle connection 22. The forward end 23 of the lever 20 is forked and provided with a downwardly curved portion 23a arranged below the rollers 24. The upper end of the stem 11 is rectangular as shown at 11a. Rollers 24 are pivotally mounted at the upper end of stem 11 as shown at 11b.

The operation of the device is as follows:

When it is desired to pour the liquid from the container 1 the lever 20 is pivoted backwardly by the toggle 22. The curved surface 23a rides under the rollers 24 raising the valve 12 against the action of the spring 18. Air is admitted into the dome 5 through the inlet 16. As the container is tipped to pour out the liquid through the outlet 15, air passes from the dome into the container thereby allowing for a free flowing of the liquid.

From the foregoing it will be seen that I have provided a simple and efficient device and it is to be understood that various changes in the details may be made without departing from the spirit of the invention.

When it is desired to fill the container 1 the closure 9 is unthreaded clear of the dome 5 and moved sidewardly.

Having thus described my invention what I claim is:

1. A container having an opening at one side thereof, a dome mounted in said opening, a valve mounted in said dome, said valve having a rectangular upper end, rollers mounted on said end, a lever pivotally mounted on said dome, said lever having a forked forward end adapted to slidably receive the upper end of said valve, said forked portion being curved and adapted to ride beneath said rollers, a spring mounted in said dome adapted to close said valve, and means for moving said lever against the action of said spring.

2. In a device of the class described, including in combination, a valve body having an open top, an outlet, a valve seat, a disc mounted on said seat, a plug threaded into said body adapted to close said top, a sleeve extending inwardly from said plug, a valve stem attached to said disc extending through said sleeve, an expansion spring mounted over said sleeve in abutment with said plug and said disc, said sleeve having a recess in the lower end thereof, a gasket mounted in said recess, and an expansion spring mounted around said stem between said gasket and said disc.

3. In a device of the class described, including in combination, a valve body having an open top, an outlet, a valve seat, a disc mounted on said seat, a plug threaded into said body adapted to close said top, a sleeve extending inwardly from said plug, a valve stem attached to said disc extending through said sleeve, an expansion spring mounted over said sleeve in abutment with said plug and said disc, said sleeve having a recess 5 in the lower end thereof, a gasket mounted in said recess, an expansion spring mounted around said stem between said gasket and said disc, a forked lever pivotally mounted on said body, said stem having a rectangular upper end extending 10 through said forked portion, rollers mounted on opposite sides of said rectangular end, said forked portion being curved downwardly and adapted to ride beneath said rollers, and means for rocking said lever whereby to open said valve.
4. In a device of the class described including in combination, a valve body having an opening in its lower end, an annular extension formed on said lower end, a container having an opening therein, said extension adapted to be peened in 15 the opening of said container, a valve body having an open top, an outlet, a valve seat, a disc mounted on said seat, a plug threaded into said body adapted to close said top, a sleeve extending inwardly from said plug, a valve stem attached to said disc extending through said sleeve, an expansion spring mounted over said sleeve in abutment with said plug and said disc, said sleeve having a recess 20 in the lower end thereof, a gasket mounted in said recess, an expansion spring mounted around said stem between said gasket and said disc, said body having an outlet opening formed at one side thereof, an outlet sleeve, and means for moving said stem whereby to form communication between said inlet and said outlet sleeve. 25

CARL A. RITTER.
